UNITED STATES PATENT OFFICE.

GEORGE S. BLAKESLEE, OF OAK PARK, ILLINOIS; GEORGE R. BLAKESLEE EXECUTOR
OF SAID GEORGE S. BLAKESLEE, DECEASED.

WASHING MACHINE.

Application filed November 7, 1919. Serial No. 336,512.

To all whom it may concern:

Be it known that I, GEORGE S. BLAKESLEE, a citizen of the United States, and a resident of Oak Park, in the county of Cook and State of Illinois, have invented certain new and useful Improvements in Washing Machines, of which the following is a specification, reference being had to the accompanying drawings.

My invention, generally speaking, relates to dish washing machines, although the machine shown in the accompanying drawings and hereinafter described is designed more particularly for washing glasses. The object of my invention is to provide an improved machine for washing glasses and similar articles which will not occupy a great deal of space, or require much power to operate it, and by the use of which the articles to be washed can be easily and safely handled, and effectively and expeditiously cleansed.

I accomplish this object as illustrated in the drawings and as hereinafter described. What I regard as new is set forth in the claims.

In the drawings.

Fig. 1 is a side view of my improved machine, some parts being broken away in order to show the construction more clearly;

Fig. 2 is a top view of the machine shown in Fig. 1, but with the cover removed;

Fig. 3 is a longitudinal vertical section taken substantially on line 3—3 of Fig. 2; and

Fig. 4 is a partial vertical cross-section taken on line 4—4 of Fig. 3.

Referring to the drawings, 10 indicates a tank, which in the construction shown is formed principally of sheet metal, and is supported by legs 11. As is best shown in Fig. 3, the bottom 12 of the tank, which is preferably a casting, is provided with an intermediately disposed transversely-extending trough 13, and the adjacent portions of the bottom 12 are inclined so as to drain into said trough. The top of the tank is provided with a removable cover 14 which fits snugly in position so as to prevent water from being splashed out of the tank during the operation of the machine. A longitudinally-extending rib 15 is provided at each side of the lower portion of the tank in position to support a basket 16 of any approved type in which the glasses or other

articles to be washed are placed for the cleansing operation. Vertically-extending ribs 17 are also provided at the sides and at one end of the tank above the ribs 15 for spacing the basket away from the walls 60 of the tank. The ribs 17 are preferably formed of sheet metal bent or pressed into shape, as is best shown in Fig. 2.

Paddle wheel mechanism is provided within the trough 13 for throwing the water 65 from said trough up and dashing it into and about the glasses or other articles contained in the basket 16. This paddle wheel mechanism comprises a shaft 18 rotatably supported by the bottom 12, radial disks 19 70 fixedly mounted on said shaft by means of hubs 20, and cuplike vanes or paddles 21 which extend at opposite sides of said disks near the peripheries thereof and are preferably formed integral with said disks. As 75 shown in Fig. 2, the ends of these vanes are open to the water in the trough so that the water taken up by them is distributed laterally as well as radially. The paddle wheel mechanism is driven by means of a sprocket 80 wheel 22 mounted upon the shaft 18 and connected by means of a chain 23 with a sprocket wheel 24 mounted upon the drive shaft of a motor 25 which is secured to the under side of the bottom 12. A housing 26 85 encloses the chain 23 and the wheels 22 and 24, as best shown in Fig. 1.

Rinsing means is provided within the tank 10 for finishing the cleansing operation, comprising a transversely disposed pipe 27 90 which is provided with a plurality of openings in its upper face, as best shown in Fig. 2, through which jets of water supplied from any suitable source are thrown upward into and over the glasses or other articles in the basket 16. The pipe 27 is preferably in the form of a casting with cross-heads 28 at its ends, the cross-heads being provided with rollers 29 which bear upon longitudinally-extending ribs or tracks 30 secured to the side walls of the tank at a lower level than the basket-supporting ribs 15. By this means the pipe 27 is adapted to be moved longitudinally of the tank underneath a basket 16 for throwing rinsing water from said pipe progressively into contact with the glasses along the whole length of the basket. The pipe 27 is moved for this purpose by means of a cable 31, preferably in the form of a cord or a wire, the ends of which are 105 110

attached to opposite ends of an arm 32 carried by said pipe, as best shown in Fig. 3. This cable extends around four sheaves 33 appropriately located at the ends of the tank 5 so that the intermediate portion of the cable travels outside of the tank at one side thereof, as shown in Figs. 1 and 2. A handle 34 on this exterior portion of the cable serves as a means for moving it endwise to move 10 the pipe 27 backward or forward underneath the basket 16. Brackets 35 provided at suitable points serve as stops to limit the movement of the handle 34 and therefore of the pipe 27. Suitable housings 36 and 37 15 are preferably provided at the end portions of the tank to protect the sheaves 33.

Rinsing water is conducted to the pipe 27 by means of a flexible hose 38 one end of which is connected to said pipe by means of 20 a coupling 39 of any suitable description, the opposite end of said hose being connected with a valve 40 which is adapted to control the admission of water thereto from a suitable source of hot water under pressure. 25 41 indicates a coupling by which such connection may conveniently be made. The valve 40 is opened to admit water to the pipe 27 by means of a spring 42 acting through a lever 43 pivotally mounted on the valve and bearing intermediately on the valve stem 44 thereof, as shown in Fig. 3, the arrangement being such that said spring tends to hold the valve 40 open. The lever 43 is actuated in opposition to said spring to close the valve 35 40, by movement of the pipe 27 to the position shown in Fig. 3, in which position the arm 32 carried by said pipe engages the lower end of the lever 43 and rocks it far enough to release the valve stem 44 so that the valve 40 automatically closes. Preferably the lever 43 is provided with an antifriction roller 45, as shown in said figure. As will be readily understood, when the pipe 27 is in its normal or inoperative position near the left 45 hand end of the tank as viewed in Fig. 3, the lever 43 is held in position to permit the valve 40 to remain closed and no water is supplied to said pipe. When, however, said pipe is moved from that position toward the 50 basket, the lower end of the lever 43 is released so that it is actuated by the spring 42 to open the valve 40 and water under pressure is thereby supplied to the pipe 27. It is evident therefore that when the pipe 27 55 is stationary in its normal position, no water is discharged through it, but as soon as said pipe is moved under a basket, the water is automatically turned on and discharged upwardly against and over the contents of the 60 basket as the pipe is moved back and forth thereunder. This continues until the pipe is moved back into position to actuate the lever 43 to close the valve.

In using the machine a tray or basket of 65 glasses is deposited upon the ribs 15, and

the cover 14 is applied to the tank. The motor 25 is then started, the paddle wheel being driven thereby in the direction indicated by the arrow in Fig. 3, so that the water from the trough 13 is thrown upward against the glasses in the basket. Owing to the conformation of the bottom 12, the wash water thrown by the paddle wheel returns immediately to the trough so that a small quantity of water suffices, and as the paddle 70 wheel is comparatively small and rotates at high speed not much power is required to operate it. When the glasses are sufficiently cleansed, the motor 25 is thrown out of operation and the pipe 27 is moved back and forth under the basket one or more times thereby thoroughly rinsing the glasses.

In order to maintain the water in the trough 13 below the level of the shaft 18 so as to assure proper operation of the paddle 85 wheel, a suitable drain 46 is located at the lowest point of the trough 13, said drain being closed by an overflow pipe 47 the opening of which is below the level of the axis of the paddle wheel and, therefore, permits any 90 excess water to escape through the drain while at the same time maintaining the level of the water at the proper depth to secure the most efficient operation. Thus the small amount of water which is added from time 95 to time by the rinsing operation does not change the level of the water in the trough 13.

While I have particularly described the 100 illustrated embodiment of my invention, it should be understood that I do not limit myself to the specific construction shown and described as in many respects my invention is generic in character, and the claims are therefore to be construed accordingly.

What I claim as my invention and desire to secure by Letters Patent, is—

1. A washing machine comprising a tank adapted to contain wash water, a paddle wheel for throwing wash water from said 110 tank upon the articles to be cleansed, and reciprocating means adapted to travel over the tank for throwing rinsing water upon such articles.

2. A washing machine comprising a tank 115 adapted to contain wash water, means for supporting the articles to be cleansed above the water in said tank, a paddle wheel for throwing water from said tank upward upon and about such articles, and manually-controlled means adapted to be reciprocated above said paddle wheel for throwing rinsing water upon such articles.

3. A washing machine comprising a tank adapted to contain wash water, means for 125 supporting the articles to be cleansed above the water in said tank, means for throwing water from said tank upon and about such articles, and means arranged to travel between said water throwing means and the 130

articles to be washed for throwing rinsing water upon said articles.

4. A washing machine comprising means for supporting the articles to be washed, 5 traveling means for throwing water upon such articles, means for supplying water to said traveling means, and means actuated by movement of said traveling means to a certain position for shutting off the supply of 10 water thereto.

5. A washing machine comprising means for supporting the articles to be washed, traveling means for throwing water upon such articles, a valve for controlling the supply 15 of water to said water throwing means, said valve being normally open when said water throwing means is traveling, and means actuated by the movement of said water throwing means to its inoperative position 20 for closing said valve.

6. A washing machine comprising a reciprocating water discharging member, means for moving said member into and out of its operative position, and means operated by 25 the movement of said member away from its inoperative position for admitting water thereto.

7. A washing machine comprising a reciprocating spraying device, a valve controlling 30 the supply of water thereto, a flexible hose connection between said valve and said spraying device, and means controlled by the position of said spraying device for operating said valve.

35 8. A washing machine comprising a tank, a traveling spraying device therein, means supporting said spraying device as it travels, a cable extending outside of the tank and having both its ends connected with said 40 spraying device, guides around which said cable extends whereby said spraying device may be reciprocated by means of said cable, and means for supplying water to said spraying device.

45 9. A washing machine comprising a tank, a traveling spray pipe extending horizontally thereover, means supporting the end portions of said pipe, a cable extending outside of the tank and having both its ends 50 connected with said spray pipe, guides around which said cable extends whereby said spray pipe may be reciprocated by means of said cable, and means for supplying water to said spray pipe.

55 10. A washing machine comprising a tank, a perforated pipe extending across the tank and adapted to be reciprocated thereover, tracks at the sides of the tank for supporting the end portion of said pipe, manually-operated means for giving said pipe a

reciprocatory movement along said tracks, and means for supplying water to said pipe.

11. A washing machine comprising a tank, a perforated pipe adapted to be reciprocated therein, tracks for supporting 65 said pipe, manually-operated means for giving said pipe a reciprocatory movement along said tracks, means for supplying water to said pipe, and means operated by the movement of said pipe to an inoperative 70 position for shutting off the supply of water thereto.

12. A washing machine comprising a tank, a perforated pipe adapted to be reciprocated therein, cross-heads on the end 75 portions of said pipe, rollers rotatably mounted on said cross-heads, tracks at the sides of the tank on which said rollers travel, manually-operated means for reciprocating said pipe, a flexible hose for supplying water to said pipe, and a valve controlling the admission of water to said hose.

13. A washing machine comprising a tank, a perforated pipe adapted to be reciprocated therein, cross-heads on the end 85 portions of said pipe, rollers rotatably mounted on said cross-heads, tracks on which said rollers travel, manually-operated means for reciprocating said pipe, a flexible hose for supplying water to said pipe, a 90 valve controlling the admission of water to said hose, and means operated by the movement of said pipe away from its inoperative position for opening said valve.

14. A washing machine comprising a 95 tank adapted to contain wash water, a support in said tank for the articles to be cleansed, means for throwing wash water from said tank upon and about such articles, and alternative means for throwing rinsing water upon such articles, comprising 100 a spraying device movable along said support over said wash water throwing means, and movable out of the way so as not to interfere with the operation thereof. 105

15. A washing machine comprising a tank adapted to contain wash water, a support in said tank for the articles to be cleansed, means for throwing wash water from said tank upon and about such articles, alternative means for throwing rinsing water upon such articles, comprising a spraying device movable along said support over said wash water throwing means, and movable out of the way so as not to interfere with the operation thereof, and means acting automatically to shut off the water from said spraying device when it is moved into an inoperative position. 110 115

GEORGE S. BLAKESLEE.
